UNITED STATES PATENT OFFICE.

JOHN ARTHUR THOMAS, OF MILLVILLE, FLORIDA.

MUSIC-LEAF TURNER.

1,354,860.

Specification of Letters Patent. Patented Oct. 5, 1920.

Application filed April 10, 1919. Serial No. 289,171.

To all whom it may concern:

Be it known that I, JOHN ARTHUR THOMAS, a citizen of the United States, residing at Millville, in the county of Bay, 5 State of Florida, have invented a new and useful Music-Leaf Turner; and I do hereby declare the following to be a full, clear, and exact description of the invention, such as will enable others skilled in the art to 10 which it appertains to make and use the same.

This invention relates to music-leaf turners and is particularly an improved device of this character.

15 Its principal object is to remove, with its consequent distraction to the musical performer, the necessity for having to take individual sheets of a piece of music between the fingers in order to turn them.

20 A further object is to provide a device of this kind that will meet the variations in size of the different sheets of music it is required to hold.

A still further object is to provide a device 25 that can be placed on a piano or similar musical instrument without attachment thereto, or that can be used in a horizontal position when conditions require.

A fourth object is to provide for the 30 quick and ready attachment of any piece of music that it is desired to place on the device.

The drawings illustrate a particular design 35 from which the requirements of practice may necessitate some deviations. These the right is claimed to make, provided they do not depart from the spirit of the appended claim.

The same numerals of reference design- 40 ate the same parts throughout the drawings, wherein:

Figure 1 is a perspective view of the invention.

Fig. 2 is a section on the line 2—2 of 45 Fig. 1.

Fig. 3 is a bottom plan view.

Fig. 4 is a section on the line 4—4 of 50 Fig. 1.

Fig. 5 is a section through a compartment 55 containing the hand-operated plungers, this section being taken transversely across the telescopic shaft.

Fig. 6 is a section on the line 6—6 of Fig. 2.

Fig. 7 is a plan view of the leaf-turning 55 arm.

Fig. 8 is a sectional view of the clamping means for attaching the leaf-turning arm to its attendant shaft.

The main platform 1 is designed to be 60 made by turning its four edges under and around the rods 2. At the four corners of 1 and abutting the under-turned edges of it, the angle braces 3 are attached by suitable rivets. Rectangular holes 4 are 65 punched near the edges of 1 which edges are considered the sides of the platform 1. These holes 4 are arranged one above the other, the lowest hole 4 being close to the bottom of 1. At that edge of 1 which is 70 considered its top a large rectangular hole is punched and this hole is covered with a pan-like device 5 whose flanges are riveted to or secured in any other suitable way to the bottom of the platform 1. Ribs 6, U- 75 shaped in section and having appropriate flanges formed on them, are secured to the under-side of platform 1 on either side of its vertical center. These ribs are for strengthening purposes and are so placed as 80 to best resist the strains to which the platform 1 is subjected. The legs 8 are of the outline shown in Fig. 1 and are riveted on the face of the platform 1, being covered with an appropriate rubber covering 7 held 85 at one end of the leg by the bent-in portion thereof and at the other end by the rivets which attach the leg. On the bottom of 5 appropriate rivets attach the rubber feet 9, the head of the rivet setting well under 90 the bottom surface of the feet.

The rest 10 is a long angular piece with hooks formed at each end for engagement in the holes 4. Nearer the center of 10 and on the bottom of the flange 11 the hinge- 95 straps 12 are riveted and these straps support the clamp which holds the lower edges of the music. The clamp is made of wire of any suitable material and has its ends 13 turned at right angles to the longitudinal 100 piece 14 which pivots in the hinges 12. Adjacent to one end of 14 the bend 15 is formed to provide a finger-hole. At the end remote from 15 a U-shaped bend 16

is formed on the cross-piece of which a spring 17 is attached, the free end of this spring hooking over a rivet or pin 18 connected in the lower edge of 11. This 5 spring serves to hold the piece 13 against the rest 10 and is the means for clamping the lower edges of the outside sheets of the piece of music thereon.

At the upper edge of the platform is a 10 clamp similar to the lower clamp and performing the similar function. It is comprised of the longitudinal piece 18 with the U-shaped bend 20 formed therein and the arms 19 and is attached to 1 by the hinges 21. A spring 22 connected between the cross-piece of the bend and the platform 1 serves to keep the upper clamp normally in the position, shown in Fig. 1 with the arms 19 close to the platform against which 20 they are designed to hold the upper edges of the outside sheets of the piece of music.

Arms 23 are designed for holding the individual sheets of the piece of music and are connected one to each shaft of a set of telescopic shafts 24, 25 and 26. Arms 23 are provided at their ends where they connect with these shafts with the clamp rings 27 through the ears 28 of which a screw 29 operates to hold them frictionally connected to 30 the particular shaft to which they are joined. Where the arm 23 is designed to connect with individual sheets it is formed into the double U-shaped members 30 and 31. This forming of the members 30 and 31 is done by 35 a bending process performed upon the end of the arm 23, the bend terminating in the eye 33. Superimposed on the members 31 and 30 is a rectangular clamp 32. This clamp is bent around the cross-piece of the 40 U-shaped member 30 in such a manner as to have a pivotal connection therewith. Torsional springs 35 held by the cross-piece of the U-shaped member 30 and pressing on the loop 34 of 32 and on the cross-piece of the 45 U-shaped member 31 keep the clamp 32 in contact with these aforementioned U-shaped members. The clamp 32 has the two ends of the material of which it is formed joined by the tubular piece 33.

50 At the bottom of the platform 1 are two housings 36 and 37 and they are connected respectively to the bottom and to the top of said platform by means of bolts or rivets 38 which pass through their flanges 39 and 40 and through the platform. Pivotally connected in one side of the housing 37 and in one flange of the pan 5 is the shaft 24. In surrounding relations to 24 the shafts 25 and 26 are mounted, room being provided 55 through a side of 37 and through a flange of 5 large enough for the outermost shaft 26 to pass through. Gears 41 are connected on to each of the shafts 24, 25 and 26. The gear on shaft 24 is connected to it at a point 60 joining its pivotal connection in the housing 65

37. The shaft 25 has its end brought close to but not in binding relation to the gear on 24. One of the gears 41 is connected to 25 at a point substantially in the vertical center of the housing 37 and the end of the 70 shaft 26 is brought close to but not in binding relation to it. A gear is connected to 26 at the point where 26 leaves the housing 37. It will be seen that this arrangement permits the free movement of any one of the 75 three telescopic shafts and at the same time provides against any undue longitudinal movement. Both housings 36 and 37 are provided with slides 42 on their interior and in these slides the racks 43 move. Racks 42 80 are adapted to engage the gear 41 in pairs each rack being provided with a plunger 44 and a finger-push 45.

The depression formed in the platform 1 by the pan 5 provides means for keeping the 85 arms 23 substantially below the level of the platform.

When it is desired to use this device, the rest 10 is first adjusted to suit the length of the piece of music by hooking it in any 90 pair of the several holes 4. The music is then opened and the lower edges of the outside sheets are placed under the ends 13 of the lower clamp. The upper edges of the outside sheets are placed under the arms 19 95 of the upper clamp. Individual sheets are then connected to the arms 23 by use of the clamps 32. When it is desired to turn the first of the individual sheets over; the lowest left-hand plunger is pressed down and its 100 attendant rack turns the gear with the shaft to which it is connected and results in turning the uppermost arm 23 which carries the sheet that it is desired to turn. The pressing down of one plunger serves to raise the opposite plunger connected to the same gear. The bottom left-hand plunger is designed to turn the first sheet, the middle plunger the second sheet and the top plunger the third sheet.

110 What is claimed is:—

A music leaf turner comprising an inclined leaf supporting base, the upper end of said base being provided with a transversely disposed depression, said depression being adapted to receive leaf engaging arms and maintain them normally below the surface of the base, said leaf engaging arms being secured to centrally disposed and downwardly extending telescopic members, the upper 115 ends of said telescopic members being disposed in the depression, the lower ends of the telescopic members being provided with gears, a casing surrounding the lower ends of the telescopic members and their gears, said casing on each side of the telescopic members being provided with guides at right angles to the telescopic members, rack bars 120 slidably mounted in said guide, each gear of the telescopic members engaging a rack 125 130

bar on each side thereof, said rack bars being so positioned that when one rack bar is depressed the opposite rack bar will be raised simultaneously with the rotation of 5 the telescopic member and the swinging of the leaf engaging member from one side to the other.

In testimony whereof I have signed my name to this specification in the presence of two subscribing witnesses.

JOHN ARTHUR THOMAS.
